UNITED STATES PATENT OFFICE.

FRANKLIN P. GILBERT, OF PALMERTON, PENNSYLVANIA, ASSIGNOR OF ONE-HALF TO
JACOB A. MOONEY, OF PALMERTON, PENNSYLVANIA.

COMPOSITION RAILROAD-TIE.

1,066,598.

Specification of Letters Patent.

Patented July 8, 1913.

Application filed October 5, 1912. Serial No. 724,077.

To all whom it may concern:

Be it known that I, FRANKLIN P. GILBERT, a citizen of the United States, residing at Palmerton, in the county of Carbon and State of Pennsylvania, have invented certain new and useful Improvements in Composition Railroad-Ties, of which the following is a specification.

This invention relates to certain new and useful improvements in composition railroad ties and it has for its objects among others to provide a simplified, cheapened and improved efficient tie of this general type which shall possess, in addition to the advantages and ends generally sought in such devices, capability of ready assemblage, adjustment of the parts, and provision for yieldingly supporting the rails, yet automatically limiting the downward movement thereof.

The tie proper is composed of sections detachably united and inclosing the springs which as the rails are depressed, contact at their ends against abutments on the tie portions.

Other objects and advantages of the invention will hereinafter appear and the novel features thereof will be particularly pointed out in the appended claims.

The invention is clearly illustrated in the accompanying drawings, which, with the numerals of reference marked thereon, form a part of this specification, and in which—

Figure 1 is a perspective view showing one of the improved ties in position, the rails being in section and one of the rail fastenings removed. Fig. 2 is a substantially central vertical longitudinal section through the tie shown in Fig. 1. Fig. 3 is a horizontal section on the line 3—3 of Fig. 2 looking in the direction of the arrows.

Like numerals of reference indicate like parts throughout the different views.

The improved tie consists of a base 1 of cement or other suitable composition, suitably reinforced, as shown at 2, and formed with steps or shoulders or abutments 3, 3 and 4, 4, upon different levels. This base member is provided with suitable openings for the passage of the bolts, as seen in Fig. 2.

A rectangular member 5 of concrete or other suitable material reinforced as at 6 rests upon the lower portion of the base and fits snugly around the next upper por-

tion and against the abutments or shoulders 3, as seen best in Fig. 2.

7 is the top portion of cement or other suitable material, reinforced, as seen at 8. This is formed with the depending portion 9 which is fitted within the rectangular portion 5 to form a closure and to snugly hold the rectangular portion, as will be readily understood upon reference to Fig. 2.

The upper face of the top or cover portion 7 is formed with the cavities or depressions 10 in which are seated the metal plates 11, the upper faces of which are corrugated, as seen in Figs. 1 and 2. These plates are provided with openings coincident with the openings in the base 1 and top or cover 7, as shown, for the passage of the bolts. These bolts 12 have their heads 13 countersunk in the under face of the base 1, as seen in Fig. 2, and their upper ends passed through elongated openings or slots 14 in the rail chairs or fastening members 15. The under faces of these chairs or members are corrugated, as seen at 16, for co-operation with the corrugations of the plates 11. Nuts 17 on the upper ends of these bolts serve to securely retain the parts in position and yet allow of the requisite downward movement of the top or cap member 7 under the weight of the passing train. Suitable washers 18 may be employed, if necessary, such being shown in Figs. 1 and 2, and against which the nuts bear. These fastenings may be of any well-known form except as herein described and clamp the rails 19 upon both sides, as will be readily understood upon reference to Figs. 1 and 2.

Within the chambers 20 formed between the base and cap or cover piece of the tie are disposed the springs 21 which have the upper flat portions 22 bearing against the under face of the top or cover portion 7, the said lower face being, if desired, rounded, as shown at 23, to conform to the curved surface of the springs at these points. The free ends of the springs are bent outwardly and in some instances upwardly, as seen at 24, the inner ends of the springs bearing against the abutments or shoulders 4 of the base plate and the outer ends against the adjacent walls of the rectangular member 5,

when the weight of the train is upon the rails. Normally these springs raise the top or cover 7 a slight distance leaving a space, as shown at 25, between the top of the

rectangular portion 5 and the adjacent wall of the top or cover 7, and when the top or cover is thus elevated, the ends of the springs are out of contact with their abutments 4 and the adjacent walls of the rectangular member 5. The bolts 12 pass loosely through openings in the flat portions of the springs, as seen in Fig. 2, so as to allow of the requisite vertical movement 10 of the parts without binding.

The parts are readily assembled, the rectangular portion being placed upon the base, the springs then applied and then the top or cap portion 7 put in position, and the 15 bolts 12, preferably also previously applied, with their heads countersunk in the under face of the base and their other ends passed through the springs and the top or cap portion and the metal plates 11, have the rail 20 fastenings applied and then the parts are all secured together by means of the nuts 17.

It will thus be seen that provision is made for ready adjustment, as well as for separation, of the parts when necessary for the 25 purpose of repairs or replacement of any of the parts and when the weight of the train is applied, the upper portion of the tie yields, being limited by the engagement of the ends of the springs against their abutments and the contact of the upper member 30 with the upper face of the rectangular member 5.

Modifications in detail may be resorted to without departing from the spirit of the invention or sacrificing any of its advantages. 35

What is claimed as new is:

1. A composition railroad tie comprising a base plate, a rectangular member supported thereon and a removable top plate 40 having depending portion receivable within the rectangular member.

2. A composition railroad tie comprising a stepped base member, a rectangular member supported on the base and engaged with 45 one of the steps thereof, and a removable top member having a depending portion received within the rectangular member.

3. A composition railroad tie comprising a stepped base member, a rectangular member supported on the base and engaged with 50 one of the steps thereof, a removable top member having a depending portion re-

ceived within the rectangular member, and springs within the rectangular member having a bearing thereagainst. 55

4. A composition railroad tie comprising a base member having shouldered portions, a rectangular member supported on the base and engaged with one of the shouldered portions, a removable top member, and springs 60 within the rectangular member and engageable therewith and with another shouldered portion of the base.

5. A composition railroad tie comprising a base, a rectangular member thereon, a top having a depending portion receivable within the rectangular portion, springs between the base and top and confined within the rectangular portion, and means passed through the base, the springs and the top 70 adjustably holding the parts in position.

6. A composition railroad tie comprising a base, a rectangular member thereon, a top, having a depending portion receivable within the rectangular portion, springs between 75 the base and top and confined within the rectangular portion, means passed through the base, the springs and the top adjustably holding the parts in position, and rail fastening members coöperating with said 80 means.

7. In a composition railroad tie, a base member, a surrounding member supported thereon, a spring supported top member, rail clamping members carried by the top 85 member, and bolts securing said parts together and allowing of vertical movement of the top.

8. In a composition railroad tie, a base member having shoulders, a surrounding member, a top, springs having flat portions upon which said top rests and having their ends extended laterally and engageable with 90 said shoulders and the surrounding member, means connecting the base and top 95 member, and rail clamping devices coöperating with said means.

In testimony whereof I affix my signature in presence of two witnesses.

FRANKLIN P. GILBERT.
